(57) **CLAIM**

The ornamental design for a mounting bracket for RFID module, as shown and described.

DESCRIPTION

FIG. 1 is a front, top, and right side perspective view of a first embodiment of a mounting bracket for rfid module showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines illustrate structure or features which form no part of the claimed design.

The dot-dash broken lines illustrate an unclaimed boundary.

1 Claim, 7 Drawing Sheets
